United States Patent Office

Des. 178,813
Patented Sept. 18, 1956

178,813

TELEPHONE-ADDRESS INDEX OR SIMILAR ARTICLE

William S. Sherman, Chicago, Ill., assignor to Cory Corporation, Chicago, Ill., a corporation of Delaware

Application April 5, 1956, Serial No. 40,937

Term of patent 14 years

(Cl. D74—1)

Fig. 1.

Fig. 2.

Fig. 3.

Fig. 4.

Fig. 1 is a top plan view of a telephone-address index or similar article, embodying my new design;

Fig. 2 is a side elevational view of the same;

Fig. 3 is a front elevational view of the same; and

Fig. 4 is a rear elevational view thereof.

I claim:

The ornamental design for a telephone-address index or similar article, substantially as shown.
